UNITED STATES PATENT OFFICE.

LINN HELANDER, OF NORWOOD, PENNSYLVANIA, ASSIGNOR TO WESTINGHOUSE ELECTRIC & MANUFACTURING COMPANY, A CORPORATION OF PENNSYLVANIA.

BLEEDER TURBINE.

Application filed August 1, 1925. Serial No. 47,509.

My invention relates to elastic fluid turbines, more particularly to turbines of the extraction or bleeder type, and has for its object the provision of apparatus of the character designated which shall be simple of design, easy of manufacture and which shall be capable of efficient operation under widely varying conditions.

More specifically the object of my invention is to provide a turbine combining a condensing section and a non-condensing section, whereby the structure of both is reduced to a minimum and either or both may be utilized to develop power at the highest efficiency.

In the accompanying drawing forming a part of this specification, Fig. 1 is a view in elevation showing an elastic fluid turbine made in accordance with my invention; and Fig. 2 is a diagrammatic view illustrating the operation of my improved apparatus.

Heretofore in the construction of bleeder turbines, as known to me, the turbine has comprised two or more sections wherein the motive fluid is at different pressures, a bleeder connection between two of the sections and leading to some point where it is desired to employ the extracted steam for heating or process purposes, and an exhaust for the completely expanded steam passing through the low pressure section of the turbine, usually connected to a condenser. In such turbines, there is also usually some dividing means between the sections behind the bleeder connection, and interstage valves are provided controlling the dividing means, the object of which is to vary the supply of motive fluid to the bleeder connection. A typical design of such apparatus is illustrated in the patent to Francis Hodgkinson, No. 1,071,420, issued Aug. 26, 1913 and assigned to the Westinghouse Electric and Manufacturing Company. Another type of bleeder turbine which has been proposed employs no dividing wall between the sections at the bleeder connection but employs a reducing valve in the bleeder line itself, designed to afford a constant pressure beyond the valve.

With either of the aforementioned types of bleeder turbines, the means for providing a constant pressure in the bleeder line affects the efficiency of the organization as a whole. The dividing wall in the turbine with its reducing valve being placed beyond

a section of the turbine where the steam has already been partially expanded and employed in doing work, affects the efficiency of the higher pressure sections in a way similar to a dam in a stream below a water wheel. It backs up the steam above it, slows down its velocity and thus subtracts from the work done in passing through the higher pressure sections. In addition to this, if the demand for bled steam is variable, the attendant variation in the pressure and temperature characteristics of the steam passing from the high pressure section to the low pressure section is undesirable.

Where a reducing valve is employed in the bleeder line, the steam pressure at the bleeder opening must be maintained higher than the pressure beyond the valve at all loads at which steam is to be bled. Since the pressure in the turbine at the bleeder opening is influenced both by the load on the turbine and the quantity of steam bled, provision must usually be made for a considerable excess of pressure ahead of the reducing valve to enable the valve to maintain a practically constant pressure in the bleeder line under varying conditions of bleeding and loading. As is well known, reducing the pressure of steam in this manner without allowing the steam to perform work entails a loss of useful energy. The loss is liable to be particularly large at high loads and when bleeding large quantities of steam.

The sacrifice of efficiency entailed in the design of such apparatus has led, in many instances, to the provision of separate relatively small non-condensing units, the total exhaust of which is utilized in the heating or process purposes. This practice, however, is open to the objection that it greatly increases the cost of the installation, necessitating as it does the provision of separate casings, rotors, bearings and governing apparatus. It is further open to the objection that valuable space needed in a power plant is taken up by the extra apparatus.

In accordance with my invention, I overcome the before-mentioned difficulties by providing a turbine which comprises a condensing section and a non-condensing section in one casing, said sections being disposed within non-communicating compartments within the casing. I further provide means whereby the control valves of the two sections may be operated by one govern-

ing mechanism to give preference in steam supply either to the condensing or to the non-condensing portions, as desired. I also provide means whereby the non-condensing section of the turbine may be run idly when bled steam is not desired, without any appreciable loss in efficiency of the apparatus.

Referring now to the drawing for a better understanding of my invention, I show in Fig. 1 a turbine 10 made in accordance with my invention and comprising a condensing section 11 and a non-condensing section 12. Motive fluid for the condensing section is admitted through a conduit 13 and after expansion in the condensing section is exhausted into a condenser 14.

Motive fluid for the non-condensing section 12 of the turbine is admitted through a conduit 16 and after partial expansion in said section is discharged to an exhaust conduit 17 through which it may be conveyed to heating apparatus, such as a feed water heater 18.

The admission of motive fluid to the condensing section 11 is controlled by an admission valve 19. This valve is controlled by a well-known form of governing mechanism at 21, which actuates the admission valve by means of a fluid pressure relay embodying a controlling or pilot valve 22 and an operating cylinder 23. Extending upwardly from the operating cylinder 23, as shown in Fig. 1, a piston rod 24 is connected to a lever 26 which is pivoted at 27 and connected at 28 to the admission valve stem.

Motive fluid for the non-condensing section 12 is controlled by an admission valve 29 located in the conduit 16. The governor 21 is also adapted to control the admission of motive fluid to the non-condensing section 12 by means of a piston rod 31 extending downwardly from the operating cylinder 23, as shown in the drawing, and connected to an operating stem 32 of the valve 29. Motive fluid admitted to the non-condensing section 12 is further controlled by an admission valve 33 arranged in series with the admission valve 29 and controlled by a well-known form of pressure-responsive device 34 which is adapted to be connected to the exhaust conduit 17 in a manner to be more fully described later.

Referring now more particularly to Fig. 2, the turbine 10 embodies a casing 36 and a rotor 37. Mounted upon the rotor 37 in the condensing section 11 is a high pressure stage 38 which may be of the impulse type. Steam is admitted to the impulse stage 38 by means of a nozzle 39 controlled by the admission valve 19. Following the impulse stage 38 of the condensing section are a plurality of reaction stages 41-41. The non-condensing section 12 of the turbine preferably comprises an impulse stage 42 to which

steam is admitted through a nozzle 43. The moving blades of the impulse stage 42 are carried by the rotor 37 and may be mounted in any suitable manner known to the art. The casing 36 is divided into non-communicating compartments by means of an annular web 44 which surrounds the rotor 37 between the impulse stage 42 and impulse stage 38. In order to minimize leakage between the two sections, suitable packing elements 46 may be provided to cooperate between the rotor 37 and the web members 44. Thus it may be seen that in operation either the condensing section or the non-condensing section may be run entirely independent of the other.

Inasmuch as there may be times when there is no demand for bled steam, it may be desirable to entirely shut down the non-condensing section 12. I therefore provide the admission conduit 16 with a hand-operated valve 47, and in the exhaust conduit 17 I provide a hand-operated valve 48. At 49 I show a three-way valve which is adapted to connect the exhaust conduit 17 to the pressure-responsive device 34 when the non-condensing section 12 is in operation. When the non-condensing section 12 is shut down and the condensing section 11 is in operation, the three-way valve 49 is arranged to connect the exhaust conduit 17, between the valve 48 and the turbine casing, with the condenser 14 so as to ensure that the impulse wheel 42 will run in a rarefied atmosphere of exhaust steam. At the same time, the valve 49 is adapted to connect the pressure-responsive device 34 with a source of higher pressure so as to ensure the closing of the pressure-controlled admission valve 33.

The three-way valve 49 may be manually operated as by a handle 51. The passages within the valve 49 are shown diagrammatically in Fig. 2, wherein the valve is indicated in the position that it occupies when the non-condensing section 12 is in operation. Connection through the valve between the exhaust conduit 17 and the pressure-responsive device 34 is made through a passage 52 and conduits 54 and 56. A second passage 53 is embodied in the valve and in this position is shown in communication with the motive fluid supply conduit 13 through a conduit 58, but in the position of the valve shown, the high pressure motive fluid cannot pass through the valve. When the valve handle 51 is turned clockwise, as shown in the drawing, until it points downwardly, the high pressure motive fluid is connected to the pressure-responsive device 34 through the passage 52 and conduit 54 and the passage 53 is adapted to connect the exhaust conduit 17 with the condenser 14 through a conduit 57.

From the foregoing description, the op-

eration of apparatus made in accordance with my invention will be apparent. Motive fluid admitted to the condensing section 11 in the turbine is controlled by the governor 21 and after expansion in said section passes to the condenser 14 in the same way as if this section comprised an independent turbine. It will be apparent, therefore, that this section of the turbine may be designed 10 with its successive stages arranged for the most efficient conversion of the available energy in the motive fluid. At the same time the non-condensing section 12 may be in operation with motive fluid admitted 15 through the conduit 16 and controlled by the valves 29 and 33. The valve 29 being under control of the governor 21, can not admit sufficient motive fluid to permit the turbine to overspeed. The admission valve 33 being 20 controlled by the pressure-responsive device 34 in communication with the exhaust conduit 17, further controls the non-condensing section 12 so that the exhaust pressure is that required for the heating or process 25 purposes for which it is utilized. Upon an increase in pressure in the exhaust conduit 17 above the setting of the pressure-responsive device 34, the valve 33 is moved in a closing direction. Upon a decrease in pressure 30 within the exhaust conduit 17 below the setting of the pressure-responsive device 34, the valve 33 is moved in an opening direction, thus providing for an even pressure of bled steam for the purposes desired. 35 In case no bled steam is required, the non-condensing section 12 may be entirely shut down by closing the valves 47 and 48. The three-way valve 49 is then turned so as to connect the conduit 17 with the condenser 40 14, ensuring that the impulse wheel 42 will run in a rarefied atmosphere of exhaust steam, reducing its windage and permitting the condensing section 11 to operate only slightly hampered by the idly-running section 12.

out impedance to the motive fluid flowing therethrough permits either or both to operate at all times at the highest efficiency.

From the foregoing it will be apparent that I have devised an improved bleeder turbine embodying a condensing section and a non-condensing section enclosed within a common casing and adapted to meet a wide variation in power and bleeder demand or both, while operating at the highest efficiency. 75

While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims. 80 85

What I claim is:

1. The combination of a turbine casing divided into compartments, a rotor with a shaft extending through the compartments, means for minimizing leakage of fluid from one compartment to the other, separate power developing sections arranged within the compartments, separate motive fluid inlets and exhaust outlets for the sections, a condenser connected to the exhaust of one of the sections, heat utilizing apparatus connected to the exhaust of another section, valve means for closing off communication between the heat utilizing apparatus and its associated section, and other valve means for closing the motive fluid inlet to said section and opening communication between the exhaust outlet of said section and the condenser. 90 95 100

2. A power developing unit comprising a 105
turbine casing, a first and a second power
developing section arranged within the cas-
ing and employing a common shaft, means
carried by the casing for dividing the sec-
tions and minimizing leakage of motive 110
fluid therebetween, a condenser receiving the
exhaust from the first section, an exhaust
conduit for the second section, separate motive
fluid inlets provided with admission 115
valves for the sections, means responsive to pressure for controlling the admission
valve of the second section, and valve means
for closing the admission valve to the second
section and connecting the exhaust conduit
with the condenser when desired. 120

3. A power developing unit comprising a turbine casing, a first and a second power developing section arranged within the casing and employing a common shaft, means carried by the casing for dividing the sections and minimizing leakage of motive fluid therebetween, a condenser receiving the exhaust from the first section, an exhaust conduit for the second section, separate motive fluid inlet conduits for the sections, an

admission valve in each of the conduits, a speed-responsive governor for controlling the admission valves, a second admission valve arranged in series with the governor controlled admission valve for the second section, a pressure-responsive device communicating with the exhaust conduit of the second section for controlling the second admission valve, valve means adapted to connect the pressure-responsive device with a

source of relatively high pressure for closing the motive fluid inlet to the second section and for opening communication between the exhaust conduit of the second section and the condenser when desired.

In testimony whereof, I have hereunto subscribed my name this twenty-fourth day of July 1925.

LINN HELANDER.
